UNITED STATES PATENT OFFICE.

JOHN B. GOLDSBOROUGH, OF BROOKLYN, NEW YORK.

UNDERPINNING.

Original application filed October 31, 1918, Serial No. 260,514. Divided and this application filed October 15, 1925. Serial No. 62,670.

This invention relates to a method of underpinning buildings and particularly buildings that are supported upon isolated columns.

5 In my copending application, Serial No. 260,514, filed October 31, 1918, there is disclosed and claimed a method of underpinning a building which consists generally of producing excavations in the earth beneath 10 and in alignment with the foundation of the building while leaving it supported above each excavation by the natural arching action of the foundation, and forming in the excavations sections of new foundation consisting of piers and arches supported by and 15 spanning the piers.

The present application, which is a division of my copending application referred to above, relates to an embodiment of the invention particularly adapted for use when the building is supported upon isolated columns. Inasmuch as the function of underpinning is to lend additional support to a structure by transferring its load to a greater 25 depth, the bearing area of its foundation must often be increased in order to readily emplace the requisite underpinning means. In order to increase the bearing area of a building sustained upon isolated foundation 30 columns, a supplemental footing is used to join the footings of the columns together in such a manner that the resultant structure is equivalent to a continuous foundation wall. When the supplemental footing has 35 been constructed between the columns to embed their footings, spaced excavations are produced underneath them which are filled with foundation material, the natural arching action of the supplementary footing 40 being sufficient to temporarily support the foundation until the underpinning operation has been completed.

The particular nature of the invention to which the specification relates as well as 45 other objects and advantages thereof will appear most clearly from a description of the preferred embodiment shown in the accompanying drawings in which like reference characters designate like parts in the 50 several views:

Figure 1 shows a foundation consisting of isolated piers;

Fig. 2 shows a supplemental footing binding the footings of the columns together;

Fig. 3 is a section of Fig. 2 along the 55 line 3-3;

Fig. 4 shows the method of constructing the underpinning beneath the footings; and

Fig. 5 shows the completed underpinning.

Referring to the drawings, the building or other structure 1 is supported upon isolated columns, two of such columns being shown and designated 2 and 2 which are supported upon footings 4 and 5, respectively. The method can also be utilized to underpin a building of this character, and the first step, whereby the bearing area of the foundation is increased, is shown in Fig. 2 where a keystone-shaped concrete supplemental footing 6 is first placed in position to join the 70 column footings 4 and 5 together. This supplemental footing is constructed by digging a trench around and between the column footings 4 and 5 without disturbing the supporting earth beneath them. In doing this, the column footings 4 and 5 are preferably undercut, as at 7 and 8, so that when the concrete is cast into place the portion between the column footings 4 and 5 serves as a key of an arch whereby the columns 2 and 75 3 are supported partially vertically and partially laterally by the concrete supplemental footing block 6, which is shown in plan in Fig. 3.

The natural arching action of the footing thus constructed bearing on the undisturbed earth beneath it is sufficient to support the building while the underpinning pier shafts are sunk directly beneath the column footings 4 and 5, preferably in the improved 80 manner disclosed in my Patent No. 1,143,184 for a method of lining an excavation and horizontal sheathing, dated June 15, 1915, or by any equivalent method of sheathing 85 which will permit a shaft to be sunk in the earth beneath a foundation without disturbing either the earth contiguous to the shaft or the foundation above it. Access to the space directly beneath the foundation is obtained by digging temporary lateral pits to 90 a depth sufficient to permit ready excavating without otherwise disturbing the earth contiguous to the foundation, which pits are subsequently filled up when the piers have 95 been emplaced.

100 The method disclosed by the aforementioned patent and illustrated in Fig. 4 consists in brief of sinking a shaft 9 in incre-

ments and lining its sides with horizontal sheathing 10 as the depth increases. Openings are preferably provided in the sheathing to permit a tamping of the earth back of the same so that it will not be permitted to settle or be otherwise disturbed. The shaft may be of any size commensurate with the existing conditions and in this case the shaft may be, for example, approximately 10 equivalent in area to the original columns 2 and 3.

Referring again to Fig. 4 it will be seen that the load of columns 2 and 3 is supported by the arching action of the unitary 15 footing consisting of the column footings 4 and 5 and the supplemental footing 6 which bears on the remaining undisturbed earth. Experience has shown that such support is sufficient to sustain the load without 20 danger of settlement of any portion of the foundation or building.

After the shafts have been sunk in the manner described, they are filled with foundation material, preferably concrete, as 25 shown in Fig. 4 to provide a pier 11 upon which the weight of column 3 is temporarily sustained by means of supports 12, which may be short I-beams as shown, or the like. The pier having been emplaced as shown 30 at 11 in Fig. 4, the haunch space between the end of supplemental footing 6, bottom of column footing 5, and top of pier 11, and containing the I-beams 12, is then filled with concrete to complete the arch shown in Fig. 35 5, and comprising the key footing 6 interposed between haunches 13 and 14 which rest upon piers 11 and 15 respectively to complete that portion of the underpinning structure.

While this specification and the accompanying drawings disclose a method of 40 binding and underpinning only two isolated foundation columns, it is to be understood that any number of similarly adjacent columns may be likewise joined and underpinned, that this disclosure relates merely 45 to a preferred embodiment of the invention which has been utilized for purposes of illustration, and that changes may be freely made in the form and method without departing from the spirit of the invention 50 within the scope of the appended claims.

I claim:

1. A method of underpinning a building supported on isolated columns, which 55 consists of bonding the footings of the columns with a supplemental footing of foundation material, excavating shafts beneath the columns while leaving them temporarily supported by the natural arching action of the

supplemental footing, and constructing supporting piers in said excavations. 60

2. The method of underpinning isolated column foundations which consists in bonding the footings of the columns with a supplemental footing, sinking spaced shafts beneath the footings, and filling said shafts with foundation material to form piers whereby the foundation load is transmitted 65 to a greater depth.

3. The method of underpinning a building supported upon isolated columns which consists in embedding the footings of a plurality of columns in a supplemental footing of foundation material, and constructing piers underneath the columns while temporarily supporting the weight of the building 70 upon the supplemental footing. 75

4. The method of underpinning and bonding isolated foundation columns which consists in embedding the bases of the columns 80 in one footing, producing excavation beneath and in alignment with the columns while leaving them supported by the arching action of the footing above each excavation as it is produced, and forming piers 85 in the excavations.

5. The method of underpinning a building supported on columns which consists in spanning the space between the footings of the columns with an arch-like beam, sinking shafts underneath the columns, the arching action of the beam temporarily supporting the column load, and forming piers in the shafts to complete the arch between the column footings and to support the column 95 load. 90

6. The method of underpinning a column foundation which consists of bonding the bases of the columns in one footing, producing spaced excavations beneath the footing 100 and in alignment with the foundation, and constructing piers in the excavations to support the foundation. 105

7. The method of underpinning a building supported by isolated columns which consists in undercutting the column footings, constructing a supplemental footing of foundation material around and between the column footings, sinking shafts directly beneath the columns, partially filling the shafts 110 with foundation material to form piers, inserting supports in the space between the column footings and the top of the piers, and filling the space with foundation material. 115

In testimony whereof I affix my signature.

JOHN B. GOLDSBOROUGH.
